US0D1003436S

(12) **United States Design Patent** (10) Patent No.: **US D1,003,436 S**
(45) Date of Patent: ** Oct. 31, 2023

(54) **SURGICAL STAPLE**

(71) Applicant: **Medline Industries, LP**, Northfield, IL (US)

(72) Inventors: **Wesley Reed**, Libertyville, IL (US); **Ryan Niver**, Glenview, IL (US); **Scott A. Goldstein**, Deerfield, IL (US)

(73) Assignee: **Medline Industries, LP**, Northfield, IL (US)

(**) Term: **15 Years**

(21) Appl. No.: **29/804,411**

(22) Filed: **Aug. 19, 2021**

(51) LOC (14) Cl. **24-02**

(52) U.S. Cl.

USPC **D24/145**

(58) **Field of Classification Search**

USPC D24/145, 155

CPC A61B 17/0642; A61B 17/0644; A61B 17/064; A61B 17/068; A61B 17/0682; A61B 2017/0641

(57) CLAIM

The ornamental design for a surgical staple, as shown and described.

DESCRIPTION

FIG. 1 is a front perspective view of a first embodiment of our new surgical staple;

FIG. 2 is a top plan view of the surgical staple of FIG. 1; FIG. 3 is a bottom plan view of the surgical staple of FIG. 1;

FIG. 4 is a front side elevational view of the surgical staple of FIG. 1, the rear side elevational view being identical; FIG. 5 is a right side elevational view of the surgical staple of FIG. 1, the left side elevational view being identical; FIG. 6 is a front perspective view of a second embodiment of our new surgical staple;

FIG. 7 is a top plan view of the surgical staple of FIG. 6; FIG. 8 is a bottom plan view of the surgical staple of FIG. 6;

FIG. 9 is a front side elevational view of the surgical staple of FIG. 6, the rear side elevational view being identical; FIG. 10 is a right side elevational view of the surgical staple of FIG. 6, the left side elevational view being identical; FIG. 11 is a front perspective view of a third embodiment of our new surgical staple;

FIG. 12 is a top plan view of the surgical staple of FIG. 11; FIG. 13 is a bottom plan view of the surgical staple of FIG. 11;

FIG. 14 is a front side elevational view of the surgical staple of FIG. 11, the rear side elevational view being identical; FIG. 15 is a right side elevational view of the surgical staple of FIG. 11, the left side elevational view being identical; FIG. 16 is a front perspective view of a fourth embodiment of our new surgical staple;

FIG. 17 is a top plan view of the surgical staple of FIG. 16; FIG. 18 is a bottom plan view of the surgical staple of FIG. 16;

FIG. 19 is a front side elevational view of the surgical staple of FIG. 16, the rear side elevational view being identical; FIG. 20 is a right side elevational view of the surgical staple of FIG. 16, the left side elevational view being identical; FIG. 21 is a front perspective view of a fifth embodiment of our new surgical staple;

FIG. 22 is a top plan view of the surgical staple of FIG. 21; FIG. 23 is a bottom plan view of the surgical staple of FIG. 21;

FIG. 24 is a front side elevational view of the surgical staple of FIG. 21, the rear side elevational view being identical; FIG. 25 is a right side elevational view of the surgical staple of FIG. 21, the left side elevational view being identical; FIG. 26 is a front perspective view of a sixth embodiment of our new surgical staple; FIG. 27 is a top plan view of the surgical staple of FIG. 26; FIG. 28 is a bottom plan view of the surgical staple of FIG. 26; FIG. 29 is a front side elevational view of the surgical staple of FIG. 26, the rear side elevational view being identical; FIG. 30 is a right side elevational view of the surgical staple of FIG. 26, the left side elevational view being identical; FIG. 31 is a front perspective view of a seventh embodiment of our new surgical staple; FIG. 32 is a top plan view of the surgical staple of FIG. 31; FIG. 33 is a bottom plan view of the surgical staple of FIG. 31; FIG. 34 is a front side elevational view of the surgical staple of FIG. 31, the rear side elevational view being identical; FIG. 35 is a right side elevational view of the surgical staple of FIG. 31, the left side elevational view being identical; FIG. 36 is a front perspective view of an eighth embodiment of our new surgical staple; FIG. 37 is a top plan view of the surgical staple of FIG. 36; FIG. 38 is a bottom plan view of the surgical staple of FIG. 36; FIG. 39 is a front side elevational view of the surgical staple of FIG. 36, the rear side elevational view being identical; and, FIG. 40 is a right side elevational view of the surgical staple of FIG. 36, the left side elevational view being identical.
